United States Patent Office

Des. 175,987
Patented Nov. 1, 1955

175,987

DINNER PLATE

Evan K. Shaw, Manhattan Beach, Robert Y. Allen, Pacific Palisades, and Melvin Shaw, Beverly Hills, Calif., assignors to Metlox Mfg. Co., Manhattan Beach, Calif., a corporation of California

Application August 23, 1954, Serial No. 31,978

Term of patent 3½ years

(Cl. D44—15)

The figure is a top plan view of a dinner plate showing our new design.

The shape of the plate is of conventional configuration when viewed from the side or bottom thereof.

We claim:

The ornamental design for a dinner plate, as shown and described.
